UNITED STATES PATENT OFFICE.

JOSEPH LEIBOWITZ, OF NEW YORK, N. Y.

SKIRT MARKER.

Application filed February 21, 1922. Serial No. 533,202.

To all whom it may concern:

Be it known that I, JOSEPH LEIBOWITZ, a citizen of the United States, residing at New York, in the county of New York and State of New York, have invented certain new and useful Improvements in Skirt Markers, of which the following is a specification.

This invention relates to improvements in skirt marking devices or gauges and more particularly to that class of devices wherein the bottom edge of a skirt may be evenly marked and gauged for the purpose of making a hem or other finish so that the same can be cut off or shortened to the proper length as desired.

The primary object of the invention is the construction of a skirt marking device including a stand or a pedestal with provision for revolving a marker or gauge circumferentially thereof when a skirt is being fitted.

Another and very important object of the invention is the construction of a skirt marking device wherein the gauge may be moved to various positions with relation to the pedestal or support so that the dress of the person will not be caught or engaged by the marker when descending from the platform.

Another and very important object of the invention is the construction of a skirt marking device wherein the parts are extremely simple, easily assembled, highly efficient in operation and use, practical, durable, capable of being manufactured of different kinds of material and consequently reducing the cost thereof whereby its commercial possibilities are greatly enhanced.

With these objects and others in view, the invention consists in the construction, and novel combination of parts hereinafter fully described, illustrated in the accompanying drawing, and pointed out in the subject matter being claimed, it being understood that various changes in the form, proportion, size and minor details of construction may be resorted to without departing from the spirit and scope of the invention.

In the drawings:

Figure 1 is a side elevation showing the marking member in its various positions.

Figure 2 is an enlarged sectional view of the platform and supporting column in its relation with the marker or gauge.

Figure 3 is a bottom plan of the platform, the column being shown in section.

Figure 4 is a detail of the rotatable supporting gauge.

Figures 5 and 6 are details of the measuring standard.

Figure 7 is a view partly in section showing the connection of the curved gauge with the top of the measuring standard and

Figure 8 is a detail view of the gauge.

Referring now to the drawings wherein like reference characters designate corresponding parts throughout the several views, 65 5 designates an annular base and 6 the radial ribs of the platform; a vertical, hollow column 7 preferably integral with the base forms a support for an enlarged, circular platform 8 which, as shown, is preferably secured to said column by screws 9 or other fastening elements constituting a rigid supporting structure on which the person stands so that the skirt may be properly measured and marked, the base being of such a width 70 75 as to prevent any possible tilting thereof by the person moving thereon from one position to another.

The top of column 7 is formed with an annular groove 10 which receives an annular ring 11, said ring being provided with a rib 12, the same being formed preferably integral with a laterally extending supporting bar or arm 13, the same being of a length so as to extend to the periphery of 80 85 the platform 8 above indicated. The supporting arm 13 is provided with a vertical extension 14 having a lug 16 formed therewith, the latter operating in the groove 17 in the lower portion of the platform 8 as 90 clearly shown by Figure 2 of the drawing. The said groove 17 acts as a guide for the supporting arm 13 when the same is rotated circumferentially of the platform as the operator continues the marking of the skirt 95 as is well understood. Within the supporting arm 13 I have provided a sliding bar 18 which permits of the movement of the gauge outwardly of the platform to the dotted line position as shown by Figure 1 and consequently avoids the possibility of the skirt catching or tearing in the gauge when the person alights from said platform. The measuring standards 20, 21 may be raised and lowered in the guide 22 mounted on 100 105 the end of the slideable bar 18 and movable therewith to various positions with respect to the platform, said standards 20, 21 being held in various positions by the thumb screws 24 as is readily understood. The upper end of the standard 21 is preferably provided with a curved gauge 25 T-shaped in

cross-section secured thereto by screws 26 or other suitable fastening elements. In the form shown by Figure 8 the said gauge 25 is provided with a squared seat portion 26^a therein permitting the same to be removed from said standard 21 when desired. While I have shown the gauge 25 as substantially T-shaped in cross section, it will be readily understood that other designs of 10 gauges may be utilized on the standard 21. By reason of this construction, the measuring standards may be conveniently moved to various positions circumferentially of the platform with rapidity and ease in marking 15 the skirt and the said standards may be raised and lowered without in any way affecting the circumferential movement of the device during the marking operation. As a matter of convenience in the manufacture 20 of the device, the platform is preferably removable and the column and base 5 constructed of light weight material, yet giving strength and rigidity to the same without making it too cumbrous and heavy. 25 In the accompanying drawings, I have illustrated my invention embodied in one form by way of example, and which construction has been found to answer to a satisfactory degree the results to be obtained. It would 30 be manifest, however, that other forms of embodiment may be adopted, and that the construction may be variously changed and modified by the skilled mechanic without departing from the limits of the invention.

Further it will be understood that the invention is not limited to any particular form of construction in the parts, except in so far as such limitations are specified in the subject matter being claimed. 35

Having thus described my invention, 40 what I claim as new, and desire to secure by United States Letters Patent is:—

1. A skirt marking device of the class described comprising a base and a platform attached thereto, said platform having an annular groove in its periphery, an annular member mounted on the base below the platform, an arm formed with said member, and provided with a vertical extension having a lug operable in the groove of said platform, and an adjustable gauge carried by the said arm. 45 50

2. A skirt marking device of the class described comprising a hollow base and column, a platform attached to said column, said platform having an annular groove in its periphery, a ring member mounted on the column contiguous to the bottom of said platform, a hollow arm formed with said ring, a bar slideable within the arm, said arm being provided with a vertical extension, a lug on said extension operable in the annular groove of said platform and a vertically adjustable gauge on the outer end of the slideable bar. 55 60 65

In testimony whereof I affix my signature.

JOSEPH LEIBOWITZ. [L.s.]
